UNITED STATES PATENT OFFICE.

JOHN A. STONE, OF DERRY, NEW HAMPSHIRE, ASSIGNEE TO IRVING L. KEITH, OF HAVERHILL, MASSACHUSETTS.

PRESS-BOARD FOR STACKS OF SOLES.

1,348,521.

Specification of Letters Patent. Patented Aug. 3, 1920.

Application filed June 23, 1919. Serial No. 306,126.

To all whom it may concern:

Be it known that I, JOHN A. STONE, a citizen of the United States, and a resident of Derry, county of Rockingham, State of New Hampshire, have invented an Improvement 5 in Press-Boards for Stacks of Soles, of which the following is a specification.

This invention primarily relates to devices used in adhesively connecting tap and 10 shank pieces, or a reinforcing sole to the soles of shoes, preparatory to the sole-attaching operation, and more particularly, where the parts to be connected are placed in stacks while the adhesive is fresh and are pressed 15 together between planks or boards and are retained in this position by a suitable strap or binding device.

More specifically the invention relates to certain improvements on the sole-pressing 20 devices shown in the patent to Brittain #1,247,214 in which the pressing devices comprise a pair of wooden planks or boards which are employed as pressing members for the stack of soles, the adjacent sides of 25 which are concave, and which are adapted to be sprung to an extent when clamped together.

The primary purpose of this construction was to secure an extra heavy pressure on 30 the toe and shank portions of the tap, but the results secured with devices of this character are not satisfactory for all classes of work of this character, and they are particularly unsatisfactory where it is desired to 35 attach a tap piece of one thickness and a shank piece of another thickness to each sole, for the reason that said devices will not conform to the different variations in height of the more or less irregular surfaces which 40 are pressed together, to cause satisfactory adhesion. Moreover, as a considerable number of soles are stacked in one pile, these differences frequently become multiplied, although one-half the soles are usually arranged 45 with the toes at one end of the board and one-half with the toes at the opposite end, to minimize this effect. Also it frequently happens that, on account of variations in thickness in the leather, the 50 stack is higher at one side than at the other, so that, with previous methods, the pressure applied at the lower side was insufficient.

The object of my invention is to provide a form of press board which is adapted for 55 use in the connection above indicated, and

which is further adapted to conform to the irregularities due to variations in thickness of the sole and of the parts which are cemented thereto, so that a substantially uniform pressure, or at least, a sufficient pressure for the purpose of securing adhesion, will be applied to all portions of the end surfaces of the stack.

I accomplish this object by providing the form of press board shown in the accompanying drawing in which:

Figure 1 is a side elevation of the device illustrating its manner of use.

Fig. 2 is a sectional view at line 2-2 of Fig. 1.

Figs. 3 and 4 are, respectively, side edge and plan views of the device.

Fig. 5 is a view of a shoe sole, indicating the character of some of the work performed.

As shown in the drawing, the press board comprises two identically formed, oblong, or rectangular shaped boards, or strips of flexible wood, *a* and *b*, (preferably of about $\frac{3}{8}$ " thick ash), which are connected at their ends, to opposite sides of a pair of cleats *c* and *d* of equal thickness and of a length equal to the width of said boards, and are held in parallel relation thereby, any suitable connecting means being employed, between said boards and cleats, such as screws or nails *e*, which will permit a slight swinging movement of the boards relative to the cleats.

The thickness of the cleats *c* and *d* is sufficient to space the boards *a* and *b* apart to an extent which will enable them to yield toward each other as much as their flexibility will permit, or as much as the necessities of their use may require, without touching one another, it being understood that this result would be secured even if the boards were not held in exact parallelism, although such arrangement is preferable for the purpose for which the device is designed.

In practice, the soles, to which a tap piece and a shank piece have been freshly cemented, as indicated in Fig. 5, are placed in a stack, and one of the pairs of boards *a* and *b* are placed on both the top and bottom thereof, or, in case the stack is small, a stiff plank of wood *f* may be employed at one end, as indicated in Fig. 1. An iron strap device *g*, of well known form is placed about the stack and locked while the stack

is compressed in a suitable press, as described in said prior patent to Brittain, so that, when the pressure is removed, the press boards will be held in clamping engagement with the stack by the strap.

Under these conditions the outer board, as *a*, which is engaged by the strap, will be sprung or bowed inward, uniformly, the greatest depression being at the middle, and 10 the inner board, which directly engages the soles, will be sprung inward according to the resistance encountered at the different points, as indicated in Fig. 1. That is, in practice, the tap pieces are usually of one thickness, 15 and the shank pieces of another, so that the extent to which the inner board will be forced to yield will be greater at points opposite the tap pieces than those opposite the shank pieces, and, while the pressure applied 20 to the higher portions will be somewhat greater than at the lower portions, the pressure which will be applied to the lower portions will be sufficient to hold these parts in sufficiently close engagement to cause satisfactory adhesion. Also, in case some of the 25 soles or taps should be of greater thickness, at one edge than at the other, then the resistance at the side of the stack having the thicker edges will be greater than that at the opposite side, so that the inner board will be 30 forced to yield to a greater extent at the side having the thicker edges, than at the other side, as indicated in Fig. 2. In other words, the inner board *b*, will yield in varying degrees at different points according to the 35 resistance to the compressing action which it may encounter, so that the resistance encountered at one portion will not prevent suitable compression at other points, which 40 offer substantially less resistance, the device thus being, to a substantial extent, self-adapting to conditions.

In case a particularly high stack of soles is built, or in case of particularly great unevenness of the soles and parts to be connected, it frequently is found desirable to in-

terpose one of the above described devices in the middle portion of the stack, as indicated in the dotted line position of Fig. 1, in which case each board which makes up the opposite 50 portions of the device, will yield according to the amount of resistance which it meets at any point, so that a suitable amount of pressure will be applied at other points.

The device is further advantageous in that 55 leather subjected to continuous pressure will yield, although it will not yield, to the full extent, at the time pressure is first applied, but as the boards, of which the device is constructed, will yield at this time, their 60 resiliency will compensate for the yielding of the leather at a later time, so that the pressure on the stack will not be substantially reduced.

I claim:—

1. A pressing device for the purpose described, comprising a pair of resilient boards disposed in parallelism and spacing devices disposed between said boards, at their ends, to hold them in spaced relation and to permit them to be flexed toward each other, at 70 points between said spacing devices.

2. A pressing device for the purpose described, comprising a pair of resilient boards disposed in parallelism, a pair of cleats 75 transversely disposed therebetween at each end and means to connect said boards and cleats to hold the boards in spaced relation and to permit them to be flexed toward each other at points between said cleats.

3. A device for pressing one end of a stack of soles, comprising a pair of oblong boards, disposed in parallelism, and cleats transversely disposed between said boards at their 85 ends and connected thereto, to hold the same in spaced relation, the work engaging board being resilient and adapted to yield toward the other board, to conform to the work.

In testimony whereof, I have signed my name to this specification.

JOHN A. STONE.
